FIG. 1

FIG. 3

FIG. 2

FIG. 1 is a perspective view of a combined portable toilet seat cover and disposable liner embodying my new design;

FIG. 2 is an exploded perspective view thereof;

FIG. 3 is a fragmentary perspective view thereof with a portion of the portable seat cover omitted to reveal the disposable liner;

FIG. 4 is a perspective view of the disposable liner;

FIG. 5 is a cross sectional view taken on line 5-5 of FIG. 1;

FIG. 6 is an exploded bottom perspective view thereof;

FIGS. 7, 8 and 9 are perspective views of the portable seat cover in successive folded positions; and

FIG. 10 is an elevational view showing the seat cover in its completely folded portable position.

The broken line representation of a water closet in FIGS. 1 and 2 is for purposes of illustration only.

I claim:

The ornamental design for a combined portable toilet seat cover and disposable liner, as shown and described.
